UNITED STATES PATENT OFFICE.

WILLIAM F. McCARTY, OF DEFIANCE, OHIO, ASSIGNOR TO DEFIANCE MACHINE WORKS,
OF DEFIANCE, OHIO, A CORPORATION OF OHIO.

MEANS FOR LUBRICATING MACHINE-TOOLS.

1,293,611.

Specification of Letters Patent.

Patented Feb. 4, 1919.

Application filed July 22, 1918. Serial No. 246,149.

To all whom it may concern:

Be it known that I, WILLIAM F. McCARTY, a citizen of the United States, and a resident of Defiance, in the county of Defiance and State of Ohio, have invented a new and Improved Means for Lubricating Machine-Tools, of which the following is a full, clear, and exact description.

The invention relates to the lubrication of machine tools, such, for instance, as shown and described in the application for Letters Patent of the United States for a horizontal boring, drilling, milling and tapping machine, Serial No. 240,655, filed by me on June 18, 1918.

The object of the invention is to provide a new and improved means for lubricating the bearings, gears and clutch members contained in the vertical adjustable head of a machine tool of the character mentioned, the arrangement being such as to insure a continuous and effective lubricating of the said parts while the machine is running and without requiring any attention from the attendant of the machine. Another object is to permit of using the lubricant over and over again thus reducing the waste of the lubricant to a minimum. Another object is to permit the use of a completely closed head or casing to prevent the entry of dust and other foreign substances into the head and to prevent the attendant from becoming entangled in the moving parts.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional front elevation of the vertical movable head of a machine tool provided with the improved lubricating means;

Fig. 2 is a sectional plan view of the same; and

Fig. 3 is an enlarged cross section of the same on the line 3-3 of Fig. 2.

The means for lubricating machine tools are shown applied to the driving mechanism for the spindle 34 of the horizontal boring, drilling, milling and tapping machine above

referred to. The spindle 34 is mounted in a closed head or casing 33 mounted to slide up or down on guideways 32 formed on the upright 31 of the body of the machine. The spindle 34 is driven from a vertically disposed revolving shaft 123 extending with its upper end into the head 33 and having its upper portion journaled in a bearing 125 arranged in the head 33, as plainly shown in Fig. 3. Near the upper end of the shaft 123 is secured a bevel gear wheel 130 in mesh with a bevel gear wheel 131 secured on a countershaft 132 journaled in bearings 133 and 134 arranged on the head 33. On the shaft 132 are secured gear wheels 135 and 136, of which the gear wheel 135 is in mesh with an intermediate gear wheel 137 in mesh with a gear wheel 138 mounted to rotate loosely on a sleeve 139 rotating with the spindle 34. The gear wheel 136 is in mesh with a gear wheel 140 mounted to rotate loosely on the sleeve 139 and the opposite faces of the gear wheels 138 and 140 are provided with clutch members 141 and 142 adapted to be engaged by clutch members 143, 144 of a double clutch 145 slideable and rotatably and rotatably connected by a key 146 with the spindle 34 and its sleeve 139.

The means for lubricating the parts contained within the head or casing 33 and described above are arranged as follows: On the upper reduced end 160 of the shaft 123 is secured the movable member 161 of a rotary pump 162 mounted within a cap 163 attached to the top of the head 33. The suction port 170 of the pump 162 is connected with a suction pipe 171 extending in close proximity to the bottom of the head or casing 33 partly filled with oil or other suitable liquid lubricant, as indicated in the drawings. The discharge port 175 of the pump 162 delivers the oil to a manifold 176 arranged in the under side of the cap 163. From the manifold 176 lead a number of pipes 180, 181, 182, 183 and 184 extending within the head 33 and of which the pipe 180 delivers oil to the bearing 134, the pipe 181 delivers oil to the bearing 150, the pipe 182 delivers oil to the bearing 133, the pipe 183 delivers oil to the bearing 151, and the pipe 184 discharges oil into the head in front of a window 190 arranged in the front of the head or casing 33 to enable the attendant of the machine to see at a glance whether the pump 162 is running or not. It is under-

stood that as long as the pump is in proper order and running, the oil discharged by the pipe 184 is visible through the window 190, but when the pump is out of order and no oil is discharged by the pipe 184 then it is an indication to the attendant that something is wrong with the pump. It will be noticed that the oil flows from the manifold 176 by gravity through the several pipes 180, 181, 182 and 183 to insure a proper lubrication of the bearings 133, 134, 150 and 151, and the oil passing out of the bearings flows down in the head 33 to be again pumped up by the pump 162 by way of the suction pipe 171. It will be noticed that sufficient oil is maintained in the head or casing 33 to keep the revolving parts on the spindle 34 and its sleeve 139 running in the oil to insure proper lubrication of the gearing and clutch mechanism. It is understood that the oil taken up by the gear wheels 135 and 140 is transmitted to the gear wheels 137, 135 and 136 to insure proper lubrication of the gear wheels. The bearing 125 receives oil by leakage from the pump 161 and the oil passing out of this bearing 125 readily finds its way to the gear wheels 130 and 131 to lubricate the same. The thrust bearings 152 and 153 run in the oil contained in the lower portion of the head or casing 33, it being understood that the lower portion of the casing forms an oil well.

From the foregoing it will be seen that a continuous and effective lubricating of the parts in the head or casing 33 is insured while the machine is running and without requiring any attention from the attendant of the machine. It will also be noticed that the lubricant is used over and over again thus reducing the waste of lubricant to a minimum. The attendant in charge of the machine can readily see at a glance whether the pump is doing its work or not. The head is completely closed to prevent dust and extraneous matter from passing into the head, at the same time protecting the attendant from injury by the running parts mounted in the head.

Having thus described my invention, I claim as new and desire to secure by Letters Patent:—

1. In a means for lubricating machine tools, the combination of a closed casing adapted to contain a liquid lubricant and provided with spindle bearings and shaft bearings, a horizontal spindle journaled in the spindle bearings, a driving gear for the said spindle adapted to run in the said lubricant, the said driving gear having a horizontal driven shaft and journaled in the said shaft bearings, a vertically disposed driving

shaft extending into the said casing and geared with the said driven gear shaft, a pump mounted in the said casing and having an actuating member rotating with the upper end of the said driving shaft, the said pump being located above the said gearing and having a suction pipe extending into the lubricant contained in the casing, a manifold into which discharges the pump, and a plurality of lubricant distributing pipes leading from the said manifold to the said bearings.

2. In a means for lubricating machine tools, the combination of a closed casing adapted to contain a liquid lubricant and provided with spindle bearings and shaft bearings, a spindle journaled in the spindle bearings, a driving gear for the said spindle and adapted to run in the said lubricant, the said driving gear having a horizontal driven shaft journaled in the said shaft bearings, a vertically disposed driving shaft extending into the said casing and geared with the said driven gear shaft, a pump mounted in the said casing and having an actuating member rotating with the upper end of the said driving shaft, the said pump being located above the said gearing and having a suction pipe extending into the lubricant contained in the casing, a manifold into which discharges the pump, a plurality of lubricant distributing pipes leading from the said manifold to the said bearings, an observation pipe extending from the said manifold and discharging into the casing, and an observation window on the said casing in front of the discharge end of the said observation pipe.

3. In a means for lubricating machine tools, the combination of a spindle head having a closed casing adapted to contain oil, horizontal bearings arranged in the said casing, a horizontal spindle journaled in sundry of the said bearings, a horizontal driven shaft journaled in others of the said bearings, a gearing connecting the said spindle with the said driven shaft, the gearing members on the said spindle extending into the oil contained in the said casing, a vertical driving shaft extending into the said casing, a pump in the upper portion of the casing and having an actuating member driven by the said driving shaft, the pump having a suction pipe extending into the oil in the casing, a manifold mounted on the casing and into which discharges the said pump, and oil distributing pipes leading from the said manifold to the said bearings to conduct the oil by gravity to the bearings.

WILLIAM F. McCARTY.
